AUTOMATIC ROLL ADJUSTMENT FOR ROLLING-MILLS.

1,145,880.

Specification of Letters Patent. Patented July 13, 1915.

Application filed March 11, 1913. Serial No. 753,628.

To all whom it may concern:

Be it known that I, WALTER R. CLARK, a citizen of the United States, residing in Bridgeport, county of Fairfield, and State 5 of Connecticut, have invented certain new and useful Improvements in Automatic Roll Adjustments for Rolling-Mills, of which the following is a full, clear, and exact description.

10 This invention relates to automatic means for adjusting relatively to each other the rolls of mills such as commonly employed for reducing comparatively thin, flexible lengths of metal.

15 The invention is primarily intended for use with stands of rolls for rolling comparatively thin strips of brass or other metal, but certain features of the invention may be used to advantage in other connections.

20 My improvements are also primarily designed for use with rolling mills arranged in tandem fashion, for simultaneous reduction of a strip or sheet fed from one mill 25 to another, but in some aspects of the invention the tandem arrangement of the mills is not essential.

25 The rolling of strip metal in thin gages has heretofore generally been confined to the use of a single rolling mill through 30 which the strip is passed to reduce its thickness, and from which the strip passes directly to the winding drum. There have recently been some attempts to roll these strips 35 by passing them through two or more sets of rolls placed in tandem with each other, but this tandem rolling has been unsatisfactory owing to the impossibility of maintaining a definite amount of slackness in 40 that portion of the strip between the two sets of rolls. In some cases the intermediate portion of the strip is subjected to too much tension, with the result that the metal is often stretched or strained beyond its elastic 45 limit, thereby causing inferior surfaces and unevenness in gage. In some instances the tension may even be sufficiently great to rupture the strip. On the other hand, if the slackness is too great the metal will loop up 50 between the different sets of rolls with almost equally undesirable results. Of course, manual speed adjustment of the respective

individual rolls has been attempted, in order to avoid these drawbacks, but it has been found impossible for the operator to so control the relative speeds of the rolls in this manner as to maintain a uniform slackness in the strip between the different sets of rolls. In other cases, where the tandem arrangement of the mills is not adopted, it 55 may be important to maintain a definite amount of slackness in a strip passing from a rolling mill to a power driven blocker or the like or in a strip being fed into a rolling mill. 60

65 The primary object of the present invention is to meet the above conditions by providing an automatic roll adjustment for a rolling mill which is controlled by variations in the slackness of the stock operated 70 on by said mill, whereby the slackness of the stock will be maintained automatically between certain definite limits. When two (or more) mills are arranged in tandem, the rolls of one mill will be automatically 75 adjusted by variations in the slackness of the strip at a point between the mills, in such a manner as to maintain a degree of slackness appropriate to the most effective operation of the mills. Of course, when 80 I refer to this desirable amount of slackness in the metal strip, I do not intend to indicate that the strip is devoid of tension, for my improved roll adjusting device is so constructed that it acts directly to tension 85 the strip to a certain definite extent. With a tandem arrangement of the mills, this definite tension of the strip is particularly conducive to the most effective operation of the second mill, and it will be maintained automatically 90 when the operation of the installation has once been properly started.

Another object of the invention is the provision of means whereby the rolls of a rolling mill may be adjusted in accordance with 95 the variations of position of a suitable controlling member engaging the stock emerging from (or passing to) said rolls.

To these and other ends, the invention consists in the novel features and combinations of parts to be hereinafter described and claimed.

In the accompanying drawing, Figure 1 is a diagrammatic plan view of a tandem

rolling mill installation embodying my invention. Fig. 2 is a diagrammatic side elevation of the parts shown in Fig. 1. Fig. 3 is a vertical transverse section through one of the mills, and Figs. 4 and 5 are details of the controlling valve.

Referring to the drawing, A indicates a rolling mill comprising a stand 10 and rolls 11 and 12, and B indicates a second rolling mill arranged tandem fashion with the first, comprising a stand 13 and rolls 14 and 15. The mill A is driven by a prime mover such as an electric motor 16, connected therewith by the usual reducing gearing, and the mill B is similarly driven by means of an electric motor 17. The particular means for driving the two mills is, however, unessential.

The strip or other stock to be rolled, passes from a holder 18 through the rolls 11, 12 and thence through the rolls 14, 15. The reduced stock emerging from the rolls 14, 15 is wound or coiled on a blocker or winder 19. Suitable guides of well known form, which it is not considered necessary to describe in detail, are associated with the respective sets of rolls and a guide roll 20 guides the metal strip as it emerges from the rolls 11, 12, while a similar guide roll 21 guides the metal as it enters the rolls 14, 15.

Referring to Fig. 3, it will be noted that the roll 11 of the mill A is adjustable vertically in its bearings by means of a power operated device 22. This device 22 comprises, in the embodiment shown, a hydraulic cylinder 23 having a piston 24 the rod 25 of which is connected with wedges 26 and 27. These wedges 26 and 27 coöperate with the bearings of the roll 11 in such a manner that when the wedges are pushed inward by the device 22, said roll 11 will be approached more closely to the lower roll 12, whereas when the wedges 26, 27, are pulled outward the roll 11 will be free to move away from the roll 12 to a certain extent. In the form shown, the piston rod 25 acts directly on the wedge 26 and the latter acts on the wedge 27 through its connection therewith by means of a rod 28. In order to vary the adjustment of the roll 11 by means of the device 22, as required by different conditions, the wedges 26 and 27 bear upon correspondingly tapered abutments 26^a and 27^a which are adjustable in a vertical direction by means of screws 29 and 30.

The ends of the hydraulic cylinder 23 are connected by means of pipes 31 and 32 respectively with an ordinary type of four-way valve 34 which is also connected with a pressure pipe 35 and an exhaust pipe 36, as shown in Fig. 2. When the valve is in the position shown in Fig. 4, the pressure pipe 35 will be in communication with the pipe 31 and the pipe 32 will be in communication with the exhaust pipe 36, whereby the piston

24 will be urged toward the left with reference to Fig. 3. When, on the other hand, the valve 34 is in the position shown in Fig. 5, the pipe 32 will be in communication with the pressure pipe 35 and the pipe 31 will be in communication with the exhaust pipe 36 so that the piston 24 will be urged toward the right with respect to Fig. 3.

The valve 34 is automatically controlled in a direct manner by variations in the slackness of the strip emerging from the mill A. To this end the valve proper has connected therewith an operating lever 37 connected by means of a link 38 to an arm 39 on a rock shaft 40. This shaft 40 carries rigid arms 41 between which is journaled a roll 42 adapted to rest on that portion of the strip intermediate the rolls A, B. One of the arms 41 is limited in its angular movement about the axis of the rock shaft 40 by means of stops 43 and 44, and a treadle 45 may be fixed to the shaft 40 for the purpose of facilitating the movement of the roll 42 into and out of tensioning position with respect to the strip.

The operation of the apparatus is substantially as follows: The strip is fed from the holder 18 through the rolls 11, 12 over the guide roll 20 and under the roller 42, the latter being raised by the treadle 45. The forward end of the strip is then passed over the guide roll 21, through the rolls 14 and 15 and onto the winder 19. The treadle is then depressed to carry the roll 42 down on to the strip. The rolls 11, 12 are adjusted relatively to each other for the normal reduction which is desired, by means of the manually adjustable screws 29 and 30. Both mills are then started, the speeds of the motors 16 and 17 being suitably chosen or adjusted. The slack portion of the strip between the two mills supports the controlling roller 42, and the weight of this roller is so chosen that it will tension the strip to a certain definite degree conducive to the most effective operation of the mill B. Under normal conditions, the mill A will not tension the stock entering the mill B and the tension on the latter will be solely regulated by the weight of the tension member 42. This condition is maintained automatically by the connection of the tension member 42 with the four-way valve 34, for if the slackness of the strip tends to decrease below the normal, the member 42 will be raised by the tightening of the strip thereby shifting the valve 34 (through the connections 41, 40, 39, 38 and 37) into a position wherein motive fluid will be admitted to the pipe 32, as shown in Fig. 5, whereby the piston 24 will be thrust toward the right with reference to Fig. 3. Hence the wedges 26 and 27 will be moved outward to a certain extent relatively to their openings in the stand and the roll 11 will be permitted to move away from the

roll 12 so that the tension will be relieved. On the other hand, if the slackness of the intermediate portion of the strip tends to increase beyond the normal, the four-way valve 34 will be moved in an opposite direction so that the wedges 26 and 27 will be thrust inward to approach the roll 11 closer to the roll 12. In this manner the reduction effected by the mill A will be increased so that it will operate more slowly relative to the mill B, thereby causing the superfluous slackness of the strip to be quickly taken up. Hence it will be understood that by the described arrangement of the parts the reduction effected by the mill A will be so controlled in an automatic manner by variations of slackness in the strip emerging from said mill, that the slackness of the strip between the mills will be kept practically constant. As a result, it will be impossible for the strip to be strained or ruptured between the mills, and on the other hand, it will be impossible for it to loop up between the mills to an inconvenient or undesirable extent.

As previously stated, I do not wish to limit myself in all aspects of the invention to a roll adjustment for rolling mills arranged in tandem. Moreover, the invention is not necessarily restricted to the rolling of metal in strips or sheets. Manifestly the automatic roll adjustment may be applied to one or more mills of a series in which there are three or more mills arranged in tandem fashion. Various changes in these and other respects may be adopted within the scope of the invention as defined in the claims.

What I claim is:

1. The combination with a rolling mill, of a roll adjusting device therefor actuated automatically by variations in the slackness of the stock operated on by said mill; substantially as described.

2. The combination with a rolling mill, of means for adjusting the rolls of said mill relatively to each other, and a power operated device for operating said adjusting means, controlled automatically by variations in the slackness of the strip operated on by said mill; substantially as described.

3. The combination with the rolls of a rolling mill, of automatic means for approaching one of said rolls toward the other as the slackness in the stock emerging from the mill increases; substantially as described.

4. The combination with a rolling mill, and rotary means for supporting and advancing the stock issuing from said mill, of an automatic adjusting device for said mill which decreases the distance between the rolls as the stock passing from said mill to said supporting and advancing means is slackened to a predetermined extent; substantially as described.

5. The combination with a rolling mill and means for supporting the stock emerging therefrom, of means to cause an automatic separation of the rolls of said mill as the slackness in the stock emerging from said mill decreases; substantially as described.

6. The combination with a rolling mill, and means spaced from said mill for supporting the stock emerging therefrom, of mechanism for decreasing the distance between the rolls of said mill as the stock slackens between said mill and said supporting means, and for causing a separation of said rolls as such stock tightens, and means for operating said mechanism by variations in the slackness of the stock; substantially as described.

7. The combination with a pair of rolls, and means spaced from said rolls for supporting the stock emerging therefrom, of means, including an element floating on the stock between said rolls and said supporting means, to decrease the distance between said rolls as the emerging stock slackens and to increase the distance between said rolls as the emerging stock tightens; substantially as described.

8. The combination with a pair of rolls, of power-operated means for adjusting the bite of said rolls, a controller for said power-operated means adapted to rest freely against the stock while it passes through the rolls, and means for decreasing the distance between said rolls as said controller moves in one direction, and for increasing the distance between said rolls as the controller moves in the other direction; substantially as described.

9. The combination with a pair of rolls, of means for moving one of said rolls toward the other, a power operated device to actuate said means, and controlling means for said power operated device comprising an element adapted to rest on and tension the stock acted on by said rolls; substantially as described.

10. The combination with a pair of rolls, of means for moving one of said rolls toward the other, a hydraulic device to operate said means, and a controlling means for said hydraulic device including a member adapted to rest freely on the stock emerging from said rolls; substantially as described.

11. The combination with a stand of rolls, of means for moving one of said rolls toward the other, a hydraulic device for operating said means, a controlling valve for said device, and means actuated, by the stock acted on by said rolls to operate said controlling valve; substantially as described.

12. The combination with rolling mills arranged in tandem, of a roll adjusting device for one of said mills actuated automat-

ically by variations in the slackness in the stock between the mills; substantially as described.

13. The combination of rolling mills arranged in tandem, and a roll adjusting device in connection with the mill which first receives the stock, automatically controlled by variations in the slackness of the stock between said mills; substantially as described.

14. The combination of rolling mills arranged in tandem, means for driving said mills, a roll adjusting device for one of said mills, a power operated device to operate said roll adjusting device, and a controlling member for said power operated device adapted to float on the stock at a point between said mills; substantially as described.

15. The combination with a rolling mill, of power operated means to move the rolls relative to each other, a regulating device for governing the movement of said power operated means, and a controller for said regulating device, adapted to rest freely against the stock while it passes through the mill, and having a plurality of different operative positions; substantially as described.

16. The combination with a rolling mill, of a roll adjusting device therefor, means to operate said device, an element adapted to rest freely against the stock passing through said mill, and having a plurality of different positions to which it is moved by engagement with the stock as the latter passes through the mill, and means interposed between said element and the means for operating said roll adjusting device for varying the adjustment of the rolls in consonance with the various positions assumed by said element; substantially as described.

17. The combination with a pair of rolls, of power-operated means to move one of said rolls relative to the other, a regulating device for governing the movement of said power-operated means, and a controller for said regulating device which rests freely against the stock while the latter passes through the rolls, and which is movable in one direction to decrease the distance between said rolls, and in another direction to increase the distance between said rolls; substantially as described.

18. The combination of rolling mills arranged in tandem, and automatic means controlled by the stock passing through said mills for maintaining a practically constant tension in such stock, including a roll adjusting device for one of said mills; substantially as described.

19. The combination of rolling mills arranged in tandem, and automatic means for maintaining a practically constant tension in the stock between said mills, including a power operated roll adjusting device for one

of said mills, and means for controlling the same in consonance with the variations in the slackness of the stock; substantially as described.

20. The combination with a pair of rolls for reducing a flexible metal strip, of a device to support and advance the strip acted on by said rolls, and automatic adjusting mechanism for said rolls, including an element adapted to float on the strip in the interval between said rolls and said supporting and advancing device; substantially as described.

21. The combination with a pair of rolls, of means for moving one of said rolls toward the other, a power operated device to actuate said means, means to support and advance a flexible metal strip acted on by said rolls, and controlling means for said power operated device, comprising an element adapted to float on the strip in the interval between said rolls and said supporting and advancing means; substantially as described.

22. The combination with a pair of rolls, of means for moving one of said rolls relatively to the other, a power operated device to actuate said means, means to support and advance a flexible metal strip acted on by and emerging from said rolls, and controlling means for said power operated device, comprising an element adapted to float on the strip in the interval between said rolls and said supporting and advancing means; substantially as described.

23. The combination with a rolling mill, of means for supporting and advancing a flexible metal strip acted on by said mill, and mechanism for maintaining an approximately constant tension in the strip operated on by said mill, including a roll adjusting device for said mill, and a controller for said roll adjusting device adapted to float on the strip in the interval between said mill and said supporting and advancing means; substantially as described.

24. The combination with a pair of rolls for reducing a metal strip, of means for varying the distance between said rolls, a power operated device to actuate said means, a controlling member for said power operated device, adapted to engage the strip passing through the rolls, and having various positions into which it is moved by engagement with the strip, and means connecting said member in a plurality of its positions with said power operated device to cause different adjustments of the rolls as said controlling member assumes different positions; substantially as described.

25. The combination with a pair of rolls for reducing a length of stock, of power operated adjusting mechanism for said rolls, a member adapted to engage the stock passing through said rolls, and means for translat-

ing movements of said member into movements of said roll adjusting mechanism; substantially as described.

26. The combination with a pair of rolls 5 for reducing a metal strip, of means for varying the distance between said rolls, a power operated device to actuate said means, a regulating device for said power operated device, a member adapted to engage the strip passing through said rolls, and means for converting movements of said last named member into movements of said regulating device; substantially as described.

27. The combination with a pair of rolls 15 for reducing a metal strip, of means to vary the distance between said rolls, a regulating device for said means, a roller adapted to engage the strip passing through said rolls, and means for moving said regulating de-

vice automatically in consonance with variations of position of said strip-engaging roller; substantially as described.

28. The combination with a pair of rolls for reducing a metal strip, of a power operated device to vary the distance between 25 said rolls and a controller for said power operated device, adapted to engage the strip passing through the rolls, and having a plurality of different operative positions corresponding to different adjustments of the 30 rolls by said power operated device; substantially as described.

In witness whereof, I have hereunto set my hand on the 4th day of March 1913.

WALTER R. CLARK.
